Primary Examiner — Philip S Hyder*Assistant Examiner* — Roselynne Ulm Cody(74) *Attorney, Agent, or Firm* — Christopher & Weisberg, P.A.(57) **CLAIM**

The ornamental design for a mattress lift, as shown and described.

DESCRIPTION

FIG. 1 is perspective view of a mattress lift showing my new design;

FIG. 2 is another perspective view thereof;

FIG. 3 is a front elevation view thereof;

FIG. 4 is a rear elevation view thereof;

FIG. 5 is a side elevation view thereof;

FIG. 6 is a top plan view thereof; and,

FIG. 7 is a bottom plan view thereof.

The broken lines, which define the bounds of the claimed design, form no part thereof.
